UNITED STATES PATENT OFFICE.

KNUT E. T. JOHNSON, OF NEW YORK, N. Y.

MEANS FOR GRINDING PARABOLIC SURFACES.

1,325,789.

Specification of Letters Patent. Patented Dec. 23, 1919.

Application filed March 13, 1918. Serial No. 222,252.

To all whom it may concern:

Be it known that I, KNUT E. T. JOHNSON, subject of the King of Sweden, residing at New York city, in the county of New York and State of New York, have invented new and useful Improvements in Means for Grinding Parabolic Surfaces, of which the following is a specification.

This invention comprises a device which 10 is designed to grind and polish either the convexed or the concaved surface of a parabolic reflector for use in connection with search lights, head lights or similar light projecting devices.

15 My invention has for its object to provide a device which will accurately grind and polish the convexed and concaved parabolic surface of a reflector of any predetermined directrix and focus, and to accomplish the above by mechanism which operates automatically when the required dimensions are determined upon, and the mechanism is set to correspond with those dimensions, the polishing and grinding 25 mechanism maintaining the correct angle with relation to the surface to be polished at all times during the operation.

My means of accomplishing the foregoing objects may be more readily understood by 30 having reference to the accompanying drawings which are hereunto annexed, forming parts of this specification, in which—

Figure 1 illustrates a top plan view of the mechanism with parts broken away and 35 partly in section;

Fig. 2 illustrates a side view of a portion of the mechanism being broken away and shown in section;

Fig. 3 illustrates an end elevation of the 40 mechanism, the supporting bed being shown in section, and

Fig. 4 illustrates a fragmentary plan view of the reflector, the reflector holding mechanism being shown in section similar to the 45 showing in Fig. 1, the position of the parts being shifted by the difference in location of the grinding and polishing means.

The frame or support for the mechanism as shown in this embodiment of the invention may consist of a lathe bed or a supporting bed similar thereto as identified by number 1 of the drawing, the said bed having a rib 2 to serve as a guide for certain parts of the mechanism which will presently 50 appear. At the end of the bed 1 is a chuck 3 designed to hold the reflector 4. I have

only illustrated a chuck for holding a reflector which is having the concaved surface ground and polished, but it will be apparent that when the convexed surface is 55 being ground and polished, a different form of chuck will have to be employed, these chucks being standard and forming no part of the present invention.

The chuck is of course to be mounted to 60 be continuously rotated while the reflector is being ground and polished.

As illustrated, the lathe bed is provided with the usual cross feed 10 which slides upon its guide 5, the cross feed being formed with a downwardly extending lug 9 extending into a guideway 6, and which has internal threads in which is mounted a feed screw 7. The said feed screw 7 is operated by the usual crank 8 which is mounted on 75 it. Means are provided for clamping the guide rigidly to the bed 1 at different positions of adjustment, the means comprising a plate 11 and a nut 12 which is mounted upon a bolt 13 which extends downwardly 80 from the guide 5. Mounted upon the lathe bed 1 adjacent the cross feed is a plate 14 which is movable longitudinally of the said bed, the plate 14 having a bolt 15 depending from it and a nut 16 mounted thereon, 85 the clamping plate 17 being located intermediate the nut 16 and the lathe bed 1, so that the plate 14 may be locked in any desired position relative to the cross feed.

Extending upwardly from the cross feed 90 10 is a pin or pivot 18 which is designed to travel on the line of the directrix while a pin or pivot 19 is fixedly mounted upon the plate 14 located at the focus of the parabola.

Links or levers 20, 21, 22 and 23 constitute what might be termed a toggle and the links 20 and 22 have ends pivoted on the stud 18 which is carried by the cross feed 10 which as stated moves along the line of 100 105 the directrix, whereas ends of the links 21 and 23 are pivoted on the stud 19 on the plate 14, the position of which is fixed by means of the bolt 15 and the nut and clamping plate 16 and 17 respectively. The end 110 of the link 20 remote from the pin 18 and the end of the link 21 remote from the pin 19 are pivotally connected together on a stud 24 which extends downwardly from a guiding member 26. The end of the stud 110 is threaded to engage a nut 24^a by which the parts are held in assembled relation. A

similar construction is employed for connecting the ends of the links 22 and 23, this construction being more clearly shown in Fig. 2 as comprising a guide 27 and stud 5 25 which has a nut 25^a threaded thereon.

An oscillatable bar 28 is mounted in the guides 26 and 27 and the said bar has an aperture 28^a for the reception of a depending stud 29. The stud 29 is connected by the 10 bridge plate 30 to the channel arm 30^a, said channel arm being an extension of the arm 30^b on the yoke 35 and the said arm and channel arm are attached together by screws 38, said channel arm 30^a having a longitudinally extending channel 31 to receive the bar 32 on which the channel arm reciprocates, it being shown in the drawing that anti-friction balls 33 are interposed between 15 the wall of the channel and the bar 32.

20 The bar 32 constitutes a support for the arm 30^b of the yoke 35 and as the cross feed is moved, the yoke 35 may move with relation to the member 32. The bar 32 is supported rigidly with respect to the cross feed 25 10 by means of the post 34 which rises from the cross feed and is connected to the said bar.

The yoke 35 has its arms 35^a and 25^b provided with pivots 37 on which the yoke 36 30 may oscillate, the said yoke 36 having an arm 39 rigidly connected to it, which arm serves to move the said yoke 36 on its pivots. A link 40 is connected to the arm 39 by the 35 pivot 41 and said link 40 is connected to the bar 28 by the pivot 42.

A grinding tool 43 is carried by a shaft 44 journaled in a bearing 45 carried by the yoke 36 and the said shaft 44 has a pulley or the like 46 by which the shaft is turned. Any 40 usual means may be employed for preventing longitudinal movement of the shaft in the bearing as it is desirable to maintain the relation of the grinding and polishing tool to the axes of the pivots 37 at all times during 45 the operation of the device.

It will be observed from the foregoing that the relation of parts is such that the axes of the pivots 37 are in vertical alignment and the grinding point of the wheel 50 should be directly in line with the axes of the said pivots, so that when this construction is followed, the relationship between the grinding point of the wheel or other polishing means and the parabolic curve of the 55 reflector being ground or polished will be automatically maintained at all times by the mechanism hereinbefore set forth.

Although I have shown and described a specific means for accomplishing particular 60 results such as the means of driving the shaft 44, it will be obvious that any suitable means for accomplishing this purpose may be employed.

The operation of the device is as follows: 65 The directrix and focus having been first

determined, the proper relationship between the pivots 18 and 19 is established. The power is applied to the lathe and the chuck 3 is rotated. The lever 8 is revolving, thus causing the rotation of the feed screw 7 70 which moves the cross feed 10 across the lathe bed 1. It will be apparent that as this movement is continued, the pivot 18 is brought nearer to the pivot 19 and that this movement will impart an oscillating movement to the links 20, 21, 22 and 23 which will operate to oscillate the guides 26 and 27 upon the bar 28, the position of which will obviously be affected, causing it to swing upon the pivot 19 until it has assumed the 80 position shown in Fig. 4. This movement, through the medium of the pin 29 and the bridge plate 30, causes the arm 30^a of the yoke 35 to slide upon the guide 32 while at the same time motion is imparted to the 85 yoke 36 through the pivot 42 operating upon the link 40 and arm 39. In this manner, the members move the pin 29 until it is directly between and in line with the pivots 18 and 19 at which points it is at the apex of the 90 parabola and therefore the pivots 37 will be in line with the center of the reflector 4.

It will be apparent that the foregoing movement operates to maintain the bar 28 and the arm 39 at all times in a parallel 95 relationship, thereby keeping the point of the polishing medium in the correct position. It will be obvious that by shifting the plate 14 in relation to the cross feed that the device may be adjusted to grind and polish parabolic surfaces of any desired degree of curvature and that the point of the grinding medium will at all times travel on the line of a true parabola.

It will be noted that if a line were drawn from the pivot 18 to the pivot 19, two right angle triangles would be formed on the opposite sides of the bar 28, the links 20 and 21 being hypotenuses of said triangles and the adjacent portion of the bar forming the bases thereof. In other words, the center line of the bar bisects the angle formed by the center lines of the links.

I claim—

1. In a device of the character described, a work holder adapted to be rotated, a pivot stationary and in a line with the apex or axis of an element to be worked, a pivot, means for mounting the pivot for movement along the line of the directrix of a parabola and at right angles to the line first mentioned, a link having one end oscillatable on the first mentioned pivot, a link having one end oscillatable on the second mentioned pivot, and means for pivotally connecting the opposite ends of the links, a reciprocating bar, means carried by the apex of the links for slidably maintaining the bar on lines which represent the sides of triangles of which the links would describe or repre-

sent the hypotenuses, a slidable member, means for communicating the motion of the bar to the slidable member, a support for the slidable member carried by the aforesaid 5 pivot carrying means pivots on the slidable member, a yoke oscillatable on the last mentioned pivots, a tool, means carried by the yoke for mounting the tool for rotation with its point of contact with the work in a 10 plane with the axis of the last mentioned pivots, and means for communicating the motion of the bar to the said yoke.

2. In a device of the character described, a bed, a work holder adapted to be mounted 5 for rotation with relation to the bed, a stationary pivot on the bed in line with the apex or axis of an element to be carried by the work holder, a cross feed movable at right angles to the line of the apex, a link 10 having one end pivotally connected to the cross feed, a link oscillatable on the stationary pivot, means for pivotally connecting the opposite ends of the links, a reciprocating bar, means carried by the apex of 15 the links for slidably maintaining the bar on lines which represent the sides of triangles of which the links would describe or represent the hypotenuses, a slidable member, means for communicating the motion of the 20 bar to the slidable member, a support for the slidable member carried by the aforesaid pivot carrying means, pivots on the slidable member, a yoke oscillatable on the last mentioned pivots, a tool, means carried by 25 the yoke for mounting the tool for rotation with its point of contact with the work in a plane with the axes of the last mentioned pivots, and means for communicating the motion of the bar to said yoke.

3. In a device of the character described, a bed, a work holder adapted to be mounted 5 for rotation with relation to the bed, a stationary pivot on the bed in line with the apex or axis of an element to be rotated with 10 the work holder, a cross feed movable at right angles to the said line of the apex, a pivot carried by the cross feed, a link having one end oscillatable on the first mentioned pivot, a link having one end oscillatable on the second mentioned pivot, means for 15

pivotally connecting the opposite ends of the links, a reciprocating bar, means carried by the apices of the links for slidably maintaining the bar on lines which represent the sides of triangles of which the links would 55 describe or represent the hypotenuses, a slidable member, means for communicating the motion of the bar to the slidable member, a support for the slidable member, carried by the aforesaid pivot carrying means, 60 pivots on the slidable member, a yoke oscillatable on the last mentioned pivots, a tool, means carried by the yoke for mounting the tool for rotation with its point of contact 65 with the work in a plane with the axis of the last mentioned pivots, and means for communicating the motion of the bar to the said yoke.

4. In a device of the character described, a work holder adapted to be rotated, a pivot 70 stationary and in a line with the axis of the element to be worked, a pivot, means for mounting the pivot for movement along the line of the directrix of a parabola and at right angles to the line of the first mentioned axis, two links, each having an end oscillatable on the first mentioned pivot, links oscillatably mounted on the second mentioned pivot, means for pivotally connecting the first and second mentioned links together 75 in pairs, a reciprocating bar, means carried by the apices of the links for slidably maintaining the bar on lines which represent the sides of triangles of which the links would describe or represent the hypotenuses, a 80 slidable member, means for communicating the motion of the bar to the slidable member, a support for the slidable member carried by the said means for mounting the pivot, a yoke oscillatably mounted on the 85 slidable member, means mounted on the yoke for rotatably supporting a tool, the relation of parts being such that the operative point of the tool contacts the work in a plane with the axis of oscillation of the yoke, 90 and means for communicating the motion of the bar to said yoke.

In testimony whereof I affix my signature.

KNUT E. T. JOHNSSON.
